UNITED STATES PATENT OFFICE.

SINCLAIR TOUSEY, OF NEW YORK, N. Y.

FIRE-CONTROL DEVICE.

1,288,761.

Specification of Letters Patent. Patented Dec. 24, 1918.

Application filed July 28, 1917. Serial No. 183,225.

To all whom it may concern:

Be it known that I, SINCLAIR TOUSEY, a citizen of the United States, and a resident of the city, county, and State of New York, have invented certain new and useful Improvements in Fire-Control Devices, of which the following is a specification.

My invention relates to devices for controlling the firing of arms and particularly to devices in which the firing of the piece is dependent upon the angle of elevation thereof.

It is well known that the trajectory of a projectile is generally a parabola, and that when the object fired at is at a great distance the barrel of the piece must be elevated accordingly. This elevation is effected by raising the rear sight of the piece so that in aiming, the resulting elevation of the front of the barrel will occur. It is necessary, however, that the person aiming the piece be able to see the object aimed at so that a line may be drawn between the two sights and the object, which will bring the barrel to the proper angle of elevation. At certain distances and under certain circumstances it is impossible and impracticable for a person aiming a piece to view the object aimed at, and it is an object of my invention to provide means which will enable the marksman to fire it when it is positioned at the proper angle of elevation, regardless of whether or not the object aimed at is visible.

In battle, a very small percentage of the shots fired are carefully directed, but the piece is held so as to direct the projectile approximately in the line toward the enemy, and the proper elevation is very often a matter of guess-work.

One of the more specific objects of my invention is to prevent the firing of the piece except when it is held at a predetermined angle of elevation. To this end, I provide a secondary controlling device for the firing mechanism in addition to the ordinary controlling device therefor. This ordinary controlling device is generally manually operated. The secondary controlling device, which I provide, is dependent for its operation upon a pendulum which is suspended so that it will always assume and retain a definite position under the action of gravity.

A further incidental object of my invention is to provide such a secondary controlling device which is adjustable so that it is

effective to release the firing mechanism at any predetermined elevation.

It is also a further object of my invention to provide such a secondary controlling device which is adjustable to a position wherein it is ineffective at all elevations to restrain the firing mechanism.

Other and further objects of my invention will appear from the following description taken in connection with the drawings forming part of this specification. Such further objects will be pointed out in the claim appended hereto.

In the drawings, in which like reference characters indicate similar parts,

Figure 1 is a partial longitudinal sectional view of the firing mechanism of a rifle which has associated with it a controlling mechanism embodying my invention;

Fig. 2 is a modification showing my invention associated with a different type of fire arm; and

Fig. 3 is a cross-sectional view on line 3-3 of Fig. 1.

While I disclose and describe my invention in connection with a rifle, it is to be understood that its adaptation is not limited to fire arms of this type, but it may be associated with any type of fire arm, whether it be a pistol, revolver, machine-gun, howitzer or cannon or fire-arm of any type whatsoever, or to any other device wherein a tube or barrel is used to give direction to a projected body.

Referring to the drawings for the purpose of disclosing the single embodiment of my invention chosen for the purpose of making it understandable, the stock of the rifle is shown at 1 and the breech mechanism to which the barrel is attached is shown at 2. The hammer 4 may be pivoted as at 5 or it may be arranged to slide longitudinally within other parts of the breech mechanism. In the form shown in Fig. 1, the hammer is provided with an integral boss 6 which has a tooth 7 into engagement with which the trigger 8 is held by the spring 9. The spring 10 acting on the roller 11 tends to force the hammer into contact with the firing pin 12. This is an ordinary mechanism, and the arm is fired by moving the trigger so that it is moved out of engagement with the tooth 7. One form of secondary fire control means for carrying out my invention comprises a circular disk 13, which is pivoted upon the screw 14 which is

threaded into the plate 15 in one side of the stock and a restraining member hereinafter described. The disk 13 is provided with a weight 14' which holds it always in a given position by the action of gravity. The disk 13 has a flange 16 on its periphery and surrounding this flange is a ring 17. Mounted upon this ring are the pointed lug 18 and the large lug 19, the functions of which will 10 be hereinafter described.

The ring 17 is provided with a slot 20 and through this slot extends a screw 21 which is threaded into the flange 16 so that it may be tightened up to clamp the ring 17 against 15 movement relatively to the disk 13. The ring 17 has upon it an arrow-head 22 and the disk 13 has upon it an elevation gage 23. The ring 17 may be slid around on the disk 13 by first tightening the screw 14 to clamp the disk stationary, and then by 20 undoing the screw 21 and sliding the ring 17 around by pressure upon the lug 24 to bring the arrow opposite the desired point on the elevation gage 23. The screw 24 is then tightened and the screw 14 loosened. The disk is then free to rotate and it will 25 remain in the desired position under the action of gravity.

A secondary restraining member 25 is 30 pivoted at 26 and has a hook end 27 engaging a projection 28 on the hammer 4. In Fig. 2 the military type of rifle is shown in which the trigger 8' is pivoted at 30 upon the sear 51 which is in turn pivoted 35 at 52 upon the frame-work and held by the sear spring 53 in such a position that the end 54 thereof engages with the lug 28' on the hammer 4.

The member 25 is provided with a lug 40 29 in the path of the lug 18 so that when the piece is brought to the proper elevation, the lug 18 engages the lug 29 and the part 27 releases the lug 28 on the hammer. If the trigger 8 has previously been 45 operated the above operation will result in a complete releasing of the firing mechanism and the piece will be fired. If the trigger has not been pulled, the trigger will keep the firing mechanism in set or 50 cocked position and the piece will not be fired. It is evident that by sliding the ring 17 around on the disk 13 to the desired position, the lug 18 will strike the lug 19 when the piece is brought to predetermined 55 elevation for the disk 13 always assumes the same position under the action of gravity. The marksman may, therefore, hold his piece above or below the desired elevation and

operate the operating mechanism, for instance, pull the trigger, and while holding 60 his piece trained in a horizontal plane toward the object, bring it toward the desired elevation, and as soon as the desired elevation is attained the piece will be fired.

In the modification shown in Fig. 2 the 65 part 27 coöperates with the part 28' in the same manner in which the part 27 coöperates with the part 28 in the construction shown in Fig. 1, the main difference in this construction being that the part 54 of the 70 sear 51 and the part 27 both coöperate with the same projection and rest side by side.

The spring 32 tends to hold the lug 29 in the path of the lug 18 and to hold the member 27 in the path of the member 28 75 on the hammer. The lug 19 is mounted upon the ring 17 so that the ring may be slid around on the disk 13 until the lug 19 engages with the lug 29 and the screws 14 and 21 are then both tightened. It will 80 be apparent that under these conditions the secondary controlling mechanism is so adjusted that the rifle may be fired at any elevation desired. It is evident that my secondary controlling means, which is effective 85 for releasing firing mechanism only upon the attainment of the proper elevation thereby, may be associated with firing mechanism of any type whether it be firing mechanism operated by an electric circuit controlled by 90 a switch, or a magneto, or any known type of firing mechanism which is, or may be, associated with projecting tubes or barrels of any type. Therefore, I do not limit myself to the particular construction disclosed, 95 but intend that my invention shall be defined only by the hereunto appended claim, and that it shall include such modifications, adaptations and variations as may occur to those skilled in the art. 100

Having thus described my invention, what I claim as new and desire to secure by Letters Patent is:

In a fire arm, a member movable to fire said piece, a trigger-operated restraining means for said member, a secondary restraining means for said member, a pendulum-operated means including a cam for causing said last-named means to release said member and a cam for rendering said 105 secondary restraining means inoperative upon a predetermined adjustment of said pendulum-operated means. 110

In testimony whereof, I have signed my name to this specification.

SINCLAIR TOUSEY.
